UNITED STATES PATENT OFFICE.

CLARENCE H. YOUNG, OF BOSTON, MASSACHUSETTS.

RACK FOR DRYING STAVES.

Application filed June 9, 1925. Serial No. 35,910.

My invention relates to racks and particularly but not exclusively to one for holding staves undergoing the process of drying in a kiln.

5 My invention will be best understood from the following description when read in light of the accompanying drawings showing one specific embodiment of my invention selected for illustrative purposes, while the 10 scope of my invention will be more particularly pointed out in the appended claims.

In the drawings:—

Fig. 1 is a perspective of the assembled rack;

15 Fig. 2 is a perspective of the main frame of the rack;

Fig. 3 is a longitudinal section of the rack constructed according to Fig. 1;

20 Fig. 4 is a section on the line 4—4 of Fig. 3; and

Fig. 5 is a section on the line 5—5 of Fig. 1.

Referring to the drawings, the base or chassis of the rack is formed of two superimposed rectangular frames, the upper frame comprising the end angle irons 1 and the side angle irons 3, and the lower frame comprising the end angle irons 5 and the side angle irons 7. The angle irons 1 as clearly shown in the drawings have their upper webs arranged horizontally and their lower webs vertically, while the angle irons 5 have their upper webs arranged vertically and their lower webs horizontally. The vertical webs of the angle irons 1 and 5 at their ends are riveted to plates 9 which extend beyond the ends of the angle irons and have secured thereto, as for example by removable bolts, angle irons 11 forming posts at the four 35 corners of the rack. The angle irons 3 and 7 each have one web arranged horizontally and riveted to the horizontal webs of the angle irons 1 and 5. Midway the length of the angle irons 3 and 7 are two pair of superimposed angle irons 13 and 15 arranged similarly to the angle irons 1 and 5 and riveted at their ends to the horizontal webs of the angle irons 3 and 7.

Extending lengthwise of the rack beneath the angle irons 5 and 15 are angle irons 17 having their upper webs horizontally positioned and riveted to the horizontal webs of the angle irons 5 and 15. Bracing the angle irons 13 and 15 to each other are short vertical angle irons 19, one of the webs of

each being riveted to the vertical webs of the angle irons 13 and 15. As best shown by Figs. 3 and 4 the angle irons 17 carry journals 21 which support the opposite end portions of the axles 23 carrying wheels 25 resting on the tracks 27.

It will be noted that the angle irons 5 and 1 secured together at their ends by means of the plates 9, and the angle irons 13 and 15 secured together by means including the angle irons 19, form structural steel girders having vertical webs and upper and lower horizontal webs to which horizontal webs the angle irons 3, 7 and 17 are secured.

At their upper ends the two posts 11 at 70 each side of the rack carry angle irons 29 arranged with their lowermost webs positioned horizontally and with their vertical webs riveted to the inside webs of the posts. Near their lower ends the two posts 11 at each 75 side of the rack carry angle irons 31 arranged with their upper webs positioned horizontally and their vertical webs riveted to the inside web of the post.

The rack carries removable unitary side 80 members comprising vertical angle irons 33 arranged in pairs back to back so as to form T-shaped structures. At opposite ends the angle irons 33 are riveted to the vertical webs of angle irons 35, the horizontal webs of the 85 angle irons 35 forming the upper and lower edges of the side members and fitting between the horizontal webs of the angle irons 29 and 31. For further bracing the angle irons 33 angle irons 37 are provided which are arranged with their upper webs vertical and their lower webs horizontal, the vertical webs resting against and being riveted to the angle irons 33. The posts carry angle irons 38 the vertical webs of which are 90 riveted or bolted to the posts and the upper horizontal webs of which form shelves on which the lower horizontal webs of the angle irons 37 rest. After the side walls are placed in position the vertical webs of the 95 angle irons 35 and 37 are bolted to the vertical webs of the posts 11.

For bracing the side walls I form a removable top frame comprising the end angle irons 39 and the side angle irons 41, these angle irons having their upper webs positioned horizontally and being riveted together at the corners, rigidity being secured by means of diagonal braces 43. As best 105 illustrated in Fig. 5 the vertical webs of the 110

angle irons 41 are secured to the vertical webs of the angle irons 29 by means of bolts or other suitable securing members, and the horizontal webs of the angle irons 29 act as 5 a shelf on which the angle irons 41 rest.

The rack is provided with a removable floor which comprises the transversely arranged horizontally disposed spaced angle irons 45 arranged with their upper webs horizontal. At the ends of the angle irons 45 are angle irons 47 arranged with one web horizontal and above the horizontal webs of the angle iron 45, the horizontal webs of the angle irons 45 and 47 10 being riveted together, and the vertical webs of the angle irons 47 forming the outside edges of the floor. When the floor is placed in position the vertical webs of the angle irons 47 rest on the horizontal webs 15 of the pair of angle irons 3 fitting between the two vertical webs of the latter. For increasing the rigidity of the base and for supporting the floor I may provide the spaced angle irons 49 arranged with one web 20 vertical and with their horizontal webs at the ends of the angle irons resting upon the horizontal webs of the angle irons 1. The vertical webs of the angle irons 49 are notched as is indicated at 51 in Fig. 3 for receiving the vertical webs of the angle irons 45. 25

In operation the staves are loaded on the rack and the rack is run along the track to the kiln, the drying medium passing upwardly through the bottom of the rack towards the top. For guiding the gases I have provided baffles in the form of plates 53 which as illustrated in Figs. 3 and 4 may be secured to the angle irons 45 at opposite 30 ends of the rack. It will be observed that the floor and side walls of the rack are so formed as to provide a reticulated structure which permits the gases to flow without material obstruction.

45 It will be observed that the side walls, the top frame, the floor, and the base may be made substantially independently as relatively thin flat sided integral structures, which enables the rack to be readily shipped in knocked down condition, the assembling 50 of the rack being readily accomplished.

Although I have described for purposes of illustration one specific embodiment of my invention it is to be understood that I am not limited thereby to its particular mechanical details, but that within the scope of my invention wide deviations may be made therefrom without departing from the spirit of my invention.

60 Claims.

1. A stave drying rack comprising in combination, a chassis formed of spaced members, wheels carried by said chassis, a reticulated floor on said chassis, walls at opposite 65 sides of said floor formed of spaced vertical

members, and bracing means connecting the upper portions of said walls.

2. A stave drying rack comprising in combination, a reticulated floor formed of spaced angle irons, a wall formed of spaced vertical 70 angle irons at the sides of said floor, and a wheeled support for said rack beneath said floor.

3. A stave drying rack comprising a floor 75 formed of spaced members extending lengthwise and crosswise of said rack wheels carried by said floor, side walls formed of spaced vertical members, and bracing members between the upper ends of said side walls.

4. A stave drying rack having a chassis 80 comprising superimposed rectangular frames formed of structural steel members at the ends and sides of said frames, means connecting each frame to the other to form a rigid girder structure, posts at each corner of said chassis, reticulated side walls carried by said posts, and a reticulated floor carried by the uppermost of said frames.

5. A stave drying rack having a chassis 85 comprising superimposed rectangular frames formed of structural steel members at the ends and sides of said frames, means connecting each frame to the other to form a rigid girder structure, posts at each corner of said chassis, reticulated side walls carried by said posts, a reticulated floor carried by the uppermost of said frames, and wheels carried by the lowermost of said frames.

6. A stave drying rack having a chassis 90 comprising superimposed rectangular frames formed of structural steel members at the ends and sides of said frames, means connecting each frame to the other to form a rigid girder structure, posts at each corner 100 of said chassis, bracing members carried by the upper portions of said posts, reticulated side walls carried by said posts, and a reticulated floor carried by the uppermost of said frames.

7. A stave drying rack having a chassis 105 comprising superimposed rectangular frames formed of structural steel members at the ends and sides of said frames, means connecting each frame to the other to form a rigid girder structure, posts at the corners of said chassis, a rectangular frame carried by the upper portions of said posts for bracing said posts, reticulated side walls carried 110 by said posts, and a reticulated floor carried by the uppermost of said superimposed rectangular frames.

8. A stave drying rack comprising in combination, a reticulated floor, posts at the corners of said floor, structural steel members carried above said floor by said posts at the upper and lower portions of said posts and having horizontal webs extending outwardly from said posts, side walls comprising 120 spaced vertical members carried at opposite 125 sides of said floor.

end portions by structural steel members having horizontal webs extending outwardly from said vertical members, and the horizontal webs of said structural steel members 5 of said side walls being carried by the horizontal webs of said members carried by said posts.

9. A stave drying rack comprising in combination, a reticulated floor, posts at the corners of said floor, structural steel members carried above said floor by said posts at the upper and lower portions of said posts and having horizontal webs extending outwardly 10 from said posts, side walls comprising spaced vertical members carried at opposite end portions by structural steel members having horizontal webs extending outwardly from said vertical members, and the horizontal webs of said structural steel members of said 15 side walls fitting between the horizontal webs of said members carried by said posts.

10. A stave drying rack comprising in combination, a reticulated floor, posts at the corners of said floor, means bracing the 20 upper ends of said posts, structural steel members carried above said floor by said posts at the lower portions of said posts and having horizontal webs extending outwardly 25 from said posts, side walls comprising vertical members held in spaced relation by means including structural steel members having horizontal webs extending outwardly 30 from said vertical members, and the horizontal webs of said structural steel members of said side walls resting upon the horizontal webs of said structural steel members carried 35 by said posts.

11. A stave drying rack comprising a chassis having at opposite sides thereof longitudinally extending members, a floor supported on said chassis, said floor comprising structural steel members at the sides of said chassis, said last mentioned members having vertical webs resting on said longitudinally 40 extending members and having horizontal webs carrying spaced members extending from one side of said floor to the other.

12. A stave drying rack comprising a chassis having at opposite sides thereof longitudinally extending angle irons with vertically and horizontally positioned webs, the horizontal webs of the respective angle irons 45 extending toward each other, a floor comprising a pair of angle irons at the side thereof having vertical webs resting on the horizontal webs of said longitudinally extending angle irons, and said floor having spaced members carried by the horizontal webs of said angle irons at the sides of said floor and extending from one angle iron of 50 said floor to the other.

13. A stave drying rack comprising a chassis having at opposite sides thereof longitudinally extending angle irons with vertically and horizontally positioned webs, the 55

horizontal webs of the respective angle irons extending toward each other, a floor comprising a pair of angle irons at the side thereof 60 having vertical webs resting on the horizontal webs of said longitudinally extending angle irons, said angle irons of said floor having horizontal webs which extend toward each other, spaced angle irons extending from one angle iron of said floor to the other, said spaced angle irons having 65 horizontal webs secured to the under side of the horizontal webs of said first mentioned angle irons of said floor.

14. A stave drying rack comprising a chassis having at opposite sides thereof longitudinally extending angle irons with vertically and horizontally positioned webs, the horizontal webs of the respective angle irons extending toward each other, a floor comprising a pair of angle irons at the side thereof 70 having vertical webs resting on the horizontal webs of said longitudinally extending angle irons, said angle irons of said floor having horizontal webs which extend toward each other, spaced angle irons extending from one angle iron of said floor to the other, said spaced angle irons having 75 horizontal webs secured to the under side of the horizontal webs of the said first mentioned angle irons of said floor, spaced angle irons carried by said chassis at right angles to said spaced angle irons of said floor and having vertical webs notched to engage the vertical webs of said spaced angle irons of said 80 floor.

15. A stave drying rack comprising a substantially rectangular chassis having at opposite sides thereof structural steel girders each with horizontal top and bottom webs, spaced angle irons with horizontal webs carried by said horizontal webs of said girders 85 at the end and intermediate portions of said girders, wheels for said chassis, and journals for said wheels carried by said angle irons carried at the intermediate portions 90 of said girders.

16. A stave drying rack comprising a substantially rectangular chassis having at opposite sides thereof structural steel girders each including a pair of parallel angle irons 105 arranged one above the other with a web of each positioned horizontally, spaced angle irons with horizontal webs carried by said horizontal webs of said girders at the end and intermediate portions of said girders, wheels for said chassis and journals for said wheels carried by said angle irons carried at the intermediate portions of said 110 girders.

17. A stave drying rack comprising a substantially rectangular chassis having at opposite sides thereof structural steel girders each including a pair of parallel angle irons arranged one above the other with a web of each positioned horizontally and with 120

their vertical webs extending toward each other, spaced angle irons with horizontal webs carried by said horizontal webs of said girders at the end and intermediate portions of said girders, wheels for said chassis, and journals for said wheels carried by said angle irons carried at the intermediate portions of said girders.

18. A stave drying rack comprising a reticulated floor and reticulated side walls, means supporting said floor in elevated position, and baffles beneath said floor for directing the drying medium toward said floor.
19. In a stave drying rack, a chassis having an upper and a lower frame, said frames being rigidly secured together, supporting wheels carried by said lower frame, and a

reticulated floor on said upper frame above the tops of said wheels.

20

20. A stave drying rack having in combination, a reticulated unitary floor, a chassis removably supporting said floor, wheels carried by said chassis beneath said floor, and side members for supporting the staves 25 against lateral displacement relative to said floor carried by said chassis.

21. A stave drying rack having in combination, a reticulated floor, side members for supporting the staves against lateral 30 displacement relative to said floor, and wheels for said rack beneath said floor.

In testimony whereof, I have signed my name to this specification.

CLARENCE H. YOUNG.
